UNITED STATES PATENT OFFICE.

FRANK P. VAVRA, OF CICERO, ILLINOIS.

MACHINE FOR COATING BLANKS WITH PARAFFIN.

1,345,719.

Specification of Letters Patent. Patented July 6, 1920.

Application filed August 9, 1918. Serial No. 249,156.

To all whom it may concern:

Be it known that I, FRANK P. VAVRA, a citizen of the United States, and a resident of Cicero, in the county of Cook and State 5 of Illinois, have invented certain new and useful Improvements in Machines for Coating Blanks with Paraffin, of which the following is a full, clear, and exact specification.

10 My invention is concerned with machines for coating cartons with paraffin, of the general type shown in the Vavra Patent 1,198,976, and is designed to produce a machine of the class described that shall be 15 simple in its construction, and yet capable of doing as good work as a more complicated one.

It is further concerned with a machine of the class described in which the position 20 of the final gaging or paraffin applying rolls can be adjusted so that the blanks will be accurately discharged into the cooling water in position so that they will be seized by the conveying cords without the necessity of 25 employing any guides between said rolls and the conveying cords.

It is further concerned with a novel structure whereby one of the gaging rolls can be supplied with its liquid paraffin from above 30 instead of depending for its supply upon the coöperating lower roll which dips into a paraffin vat beneath it.

It is further concerned with an upper 35 engaging roll that is supplied with steam on its interior so that the paraffin carried thereby cannot harden prematurely and thus prevent the top side of the carton from being properly coated.

It is further concerned with certain novel 40 combinations and details of construction, all of which will be described at length in the body of the specification and particularly pointed out in the claims.

To illustrate my invention, I annex here- 45 to four sheets of drawings in which the same reference characters are used to designate identical parts in all the figures, of which—

Figure 1 is a side elevation of one end of 50 the machine containing my invention;

Fig. 2 is a top plan view of the same;

Fig. 3 is a central vertical section on the line 3—3 of Fig. 2; and

Fig. 4 is a substantially vertical section 55 on the line 4—4 of Fig. 1.

In carrying out my invention, I employ

a cast iron frame 10, part of which is shown in the drawings, and in one end of said frame I mount a tank 11, which carries an ample supply of cold water for chilling 60 the blanks after they have been paraffined in the customary manner, and in this tank 11 at the end adjacent the coating machine, I journal a pair of rollers 12 and 13, which are driven by suitable connections, not 65 shown, from the coating machine proper, and associated with these rollers 12 and 13 are a plurality of strings or belts 14 and 15, moving as indicated by the arrows in Fig. 3, and serving to receive the cartons 70 which have just been coated with the melted paraffin, and to carry them through the bath so as to chill and fix the paraffin on the faces of the cartons.

Secured upon the end of the frame away 75 from the tank 11 is a pair of fixed brackets or castings 16 and 17, which are generally symmetrical, and which have journaled therein the shaft 18 for the feed roll 19 which coöperates with the cartons 20 piled 80 on the feed board 21, which is supported on the extensions 22 of the brackets 16 and 17. Journaled in bearings 23 and 24 secured on the top of the frame 10 to the left of the brackets 16 and 17 is the main shaft 25, 85 which has secured thereon between the bearings the lower gaging roll 26, and has secured thereon outside of the frame the spur gear wheel 27 and the beveled gear wheel 28, the latter being connected by gearing, not 90 shown, with the driving mechanism for the rolls 12 and 13, and other rolls, not shown, in the cooling tank 11. The outer end of the shaft 25 has secured thereon the necessary belt pulley or pulleys 29 to which the 95 driving belt 30 is applied in the customary manner. As seen in Fig. 3, the spur gear wheel 27 meshes with an idle spur gear wheel 31 suitably journaled upon a stud mounted in the adjacent end of the frame 10 100 and bracket 17, and meshing with a spur gear wheel 32 secured on the adjacent end of the feed roll 33, which is journaled in suitable bearings formed in the brackets 16 and 17. A pair of idle spur gear wheels 34 and 105 35 journaled upon suitable stud bearings carried by the bracket 17 connect the spur gear wheel 32 with the spur gear wheel 36 secured on the adjacent end of the shaft 18 which carries the blank feeding roller previously mentioned. An adjustable shaft or rod 37 is secured in the desired position of

105

110

adjustment in its split bearings 38 and 39 formed on the brackets 16 and 17 by the bolts 40, and has fulcrumed thereon the pairs of guide fingers 41 which have the idle 5 feeding rolls 42 journaled therein between adjacent pairs of the guide fingers and resting on top of the driven feed roller 33. Guide fingers 43 extend from the end of the board 21 to the roller 33, and another set of 10 wire guide fingers 44 are secured by coils upon the spacing rod 45 extending between the brackets 16 and 17 beneath the ends of the fingers 41. By means of the feed rolls and guide fingers thus far described, it will 15 be obvious that the blanks fed into the machine either by the action of the roller 19, or by hand, will be carried between the gaging roller 26 and the companion gaging roller 46 the shafts for which are journaled in the 20 bearings 47 and 48 which are mounted to slide in the vertical guideways 49 formed in the swinging brackets 50 and 51 which are adjustably mounted to swing on the shaft 25, as best shown in Fig. 4. The roll 46 is 25 geared to the roll 26 by the spur gear wheel 52 secured on the outer end of the shaft 53 of the gaging roll 46 meshing with the spur gear wheel 27 secured on the shaft 25 of the gaging roll 26. The bearing brackets 50 and 30 51 each have the recesses 54 therein at the bottom of the guideways 49 with the helically coiled expanding springs 55 mounted therein and reacting against the movable bearings 47 and 48. The bearings 47 and 48 35 are provided with the upwardly projecting lugs 56 surrounded by one end of the helically coiled expanding spring 57, the other end of which surrounds the reduced end 58 of the set screws 59, and coöperate with the 40 collar 60 secured on said set screw which is threaded through the removable caps 61 applied to the upper ends of the brackets 50 and 51, so that by adjusting the set screw 59, the degree of pressure of the gaging roll 45 46 on gaging roll 26 can be adjusted to a nicety.

The gaging roll 26 dips into and is supplied with paraffin 62 in the paraffin supply tank 63, which is secured between the sides 50 of the frame 10, and is provided with the steam jacket compartment 64, which is supplied with live steam through the pipe 65 opening into the bottom thereof and from which the water of condensation escapes 55 through the companion pipe 66 likewise opening into the bottom thereof. The paraffin is kept at the proper level by an overflow pipe 67 which extends up through the paraffin 62 and opens into the pipe 68 which 60 extends through the steam jacket, as clearly shown in Fig. 3.

While the gaging rolls 46 might be supplied with the melted paraffin by the action of the lower gaging roll 26 carrying a supply 65 on its felt covering 69 up to the felt

covering 70 of the roll 46, I preferably furnish an independent supply of paraffin through the following connections. Mounted in the top of the brackets 50 and 51 is a steam jacket cylinder 71, which is supplied with live steam by a short pipe 72 passed through the bracket 51 and connected by the elbow 73 with a pipe 74 leading to any suitable source of steam supply. The pipe 74 should be provided with a flexible connection to take care of the movement of the brackets 50 and 51 in the adjustment to be hereinafter explained. Mounted concentrically within the steam jacket cylinder 71 is a paraffin supply cylinder 75, which has a line of nipples in the bottom thereof extending down through a set of registering apertures in the bottom of the cylinder 71 so as to deliver the paraffin from the nipples 76 between the gaging roll 46 and the companion roll 77, which will be employed when the paraffin supply cylinder 75 is employed. The cylinder 75 is closed at its end 78, while a pipe 79 opens into its other end through the bracket 50, and this pipe 79 is provided with a shut-off valve 80 by which it is connected to the elongated Z-shaped pipe 81, the lower end of which is mounted so as to be capable of turning slightly in the elbow 82, secured on the upper end of the paraffin supply pipe 83, which will lead to a supply of paraffin under pressure, so that by opening the valve 80, the desired amount of paraffin can be allowed to flow into the cylinder 75, and be discharged therefrom 95 through the nipples 76 between the rolls 46 and 77. The elbow 82 has a branch pipe 84 leading therefrom and supplied with the shut-off valve 85 by which it is connected to the pipe 86 which extends into the machine 100 and empties into the tank 63.

The roll 77 is like the gaging rolls 26 and 46, a hollow metal roll with a coating 87 of felt or some similar fiber, and is secured on the shaft 88 which is journaled in a pair of 110 movable bearings 89 mounted in the guideways 90 formed in the brackets 50 and 51 and extending at right angles to the guideways 49. A recess 91 is formed in each of the brackets at the base of the guideways 90 and helically coiled expanding springs 92 are interposed between the apertures 91 and the adjacent sides of the bearings 89, the opposite sides of which are provided with lugs 93 which are encircled by the adjacent 120 end of the helically coiled expanding spring 94, the other ends of which surround the reduced ends of the set screws 96 which are threaded through the cap pieces 97 secured on the brackets 50 and 51. The adjacent 125 ends of the springs 95 engage the collars 98 secured on the set screws 96, so that by adjusting the set screws the roll 77 can be held with the desired tension against the roll 46, with which it moves at the same peripheral 130

velocity through the meshing of the spur gear wheel 99 secured on the end of its shaft meshing with the spur gear wheel 52 secured on the shaft 53 of the gaging roll 46.

5 By means of the connections thus described, it will be obvious that I can keep the gaging roll 46 supplied with any desired amount of paraffin applied to its fiber covering 70 without depending upon the lifting 10 action of the gaging roll 26.

As it is desirable to keep the gaging roll 46 hot so as to keep the paraffin thereon in a liquid state, especially when it is supplied from the gaging roll 26, I preferably supply the hollow interior of the roll 46 with live steam through the hollow axle 100 journaled in the bearing 48. This hollow axle is connected by the packing gland 101 with the reduced end 102 of an elbow 103, the 20 joint being made steam-tight by the packing 104 in the gland 101. A pipe 105 opening into the bottom of the elbow 103 leads to a source of steam supply, and the pipe 105 must have a joint therein so that the frames 25 50 and 51 can swing for adjustment. To remove the water of condensation, I extend up through the pipe 105 a smaller pipe 106, which has the horizontal portion 107 extending through the axle 100 and the down- 30 turned portion 108, the open end of which reaches to near the bottom of the hollow roll 46, so that the water of condensation may be siphoned out from said roll whenever it accumulates.

35 As it is important to deliver the cartons discharged from between the gaging rolls 26 and 46 as directly as possible to the receiving angle of the cords 14 and 15, I provide means for varying the angle at which 40 the frames 50 and 51 carrying these rolls shall stand, and for this purpose I provide the links 109 pivotally connected with each of the frames 50 and 51 to the handle levers 110, which are rigidly secured on the shaft

45 37. When the angle of the frames is to be changed, I loosen the bolts 40 and move the handles until the blanks are under the operating conditions then present, discharging properly into the receiving angles of the 50 cords 14 and 15, after which I tighten the bolts 40 and thus secure the frame in position.

The gaging rolls 26 and 46 are shown as hollow metal rolls and necessarily have coverings 69 and 70, respectively, of felt or some equivalent material, of say one-quarter of an inch in thickness, and these metal rolls so covered with felt and pressed together by the springs 57, act to gage the thickness 60 of the coating of paraffin applied to the cartons in a manner well known to those skilled in the art.

While I have shown and described my invention as embodied in the form which I at 65 present consider best adapted to carry out

its purposes, it will be understood that it is capable of modifications, and that I do not desire to be limited in the interpretation of the following claims except as may be necessitated by the state of the prior art. 70

What I claim as new, and desire to secure by Letters Patent of the United States is:

1. In an apparatus of the class described, the combination with a supply tank, of a 75 gaging roll rotating above but dipping into the liquid, a second gaging roll above the first geared thereto and spring pressed into substantial engagement therewith, means for feeding cartons between the rolls, and 80 means for supplying steam to the interior of the upper roll for the purpose described.

2. In an apparatus of the class described, the combination with a supply tank, of a gaging roll rotating above but dipping into 85 the liquid, a second gaging roll above the first geared thereto and spring pressed into substantial engagement therewith, means for feeding cartons between the rolls, a spreading roll journaled at one side of the 90 top roll, geared thereto and spring pressed into engagement therewith, and means for dropping melted paraffin into the angle between the last mentioned rolls.

3. In an apparatus of the class described, 95 the combination with a supply tank, of a gaging roll rotating above but dipping into the liquid, a second gaging roll above the first geared thereto and spring pressed into substantial engagement therewith, means 100 for feeding cartons between the rolls, a spreading roll journaled at one side of the top roll geared thereto and spring pressed into engagement therewith, a tube extending above the angle between the last mentioned rolls and having perforations in its under side, and means for keeping up the temperature of the tube. 105

4. In an apparatus of the class described, the combination with a supply tank, of a 110 gaging roll rotating above but dipping into the liquid, a second gaging roll above the first geared thereto and spring pressed into substantial engagement therewith, means for feeding cartons between the rolls, 115 a spreading roll journaled at one side of the top roll geared thereto and spring pressed into engagement therewith, a tube extending above the angle between the last mentioned rolls and having perforations in 120 its underside, and a steam jacket surrounding the tube for the purpose described.

5. In an apparatus of the class described, the combination with a paraffin supply tank, of a gaging roll journaled above and dipping into said tank, a framework swinging about the axis of the gaging roll as the center, a second gaging roll journaled in the swinging framework and spring pressed into substantial engagement with the first 125 130

- roll, gearing between said rolls, and means for securing the frame in any adjustment, substantially as and for the purpose described.
- 5 6. In an apparatus of the class described, the combination with a paraffin supply tank, of a gaging roll journaled above and dipping into said tank, a framework swinging about the axis of the gaging roll as the center, a 10 second gaging roll journaled in the swinging framework and spring pressed into substantial engagement with the first roll, gearing between said rolls, a shaft mounted in bearings outside of the swinging framework, arms secured to the end of the shaft, links connecting the arms to the swinging framework, a handle secured to the shaft, and means for clamping the shaft in any 15 adjustment.
- 15 7. In an apparatus of the class described, the combination with a paraffin supply tank, of a gaging roll journaled above and dipping into said tank, a framework swinging about the axis of the gaging roll as the center, a second gaging roll journaled in the swinging framework and spring pressed into substantial engagement with the first roll, gearing between said rolls, a shaft mounted in bearings outside of the swinging framework, arms secured to the end of the shaft, links connecting the arms to the swinging framework, a handle secured to the shaft, and means for clamping the shaft in any 20 adjustment.
- 20 8. In an apparatus of the class described, the combination with a pair of gaging rolls geared together, means for supplying said rolls with melted paraffin, a feed roll in advance of but substantially on the level of 45 the lower gaging roll, gearing between the feed roll and the gaging rolls, a shaft in advance of and above the feed roll, guide brackets loosely pivoted on the shaft and extending across the feed roll substantially to the 50 gaging rolls, and feeding disks journaled on the brackets and resting on the top of the feed roll.
- 25 9. In an apparatus of the class described, the combination with a pair of gaging rolls 55 geared together, means for supplying said rolls with melted paraffin, a feed roll in advance of but substantially on the level of the lower gaging roll, gearing between the feed roll and the gaging rolls, a shaft in 60 advance of and above the feed roll, guide brackets loosely pivoted on the shaft and extending across the feed roll substantially to the gaging rolls, feeding disks journaled on the brackets and resting on the top of 65 the feed roll, and guide wires extending from the feed roll to the gaging roll.
- 30 In witness whereof, I have hereunto set my hand and affixed my seal, this 7th day of August, A. D. 1918.
